WOOL COMBING MACHINE

Louis P. Miller, North Plainfield, N. J.

Application December 30, 1949, Serial No. 135,871

15 Claims. (Cl. 19—123)

1
This invention relates to textile machinery and more particularly to machinery suitable for combing wool fibers and the like.

The manufacture of worsted yarn comprises essentially cleaning the fibers, separating out and removing the short fibers, orienting the remaining fibers in parallel relation, and repeated doubling and drawing of the sliver to average out thin spots and produce a substantially uniform roving which subsequently is drafted and spun into a yarn.

In the so-called "Bradford system" the Noble comb is used for removing vegetable matter, neps and short fibers from a previously formed sliver and laying the remaining fibers parallel. Loose substantially untwisted slivers of wool are passed into a circular or Noble comb comprising a slowly rotating large outer combing circle provided with many closely spaced pins and a pair of small inner combing circles within and tangent to the outer circle which are also provided with pins, the small circles being rotated on fixed axes, the speeds of both the small and large circles at the points of tangency being substantially the same and the slivers being fed inwardly and "dabbed" into the pins of both the small and large circles at the points of tangency. Part of the combing of the wool fibers takes place as the wool is carried forward by the pins on the circles, the circles diverging from the point of tangency so as to draw out the fibers producing a combed fringe of fibers projecting from the pins of both the small and large circles. The fibers are carried by the circles to drawing off rolls and aprons which pull the fibers of the projecting fringe from between the pins of the circles and carry the fibers inwardly, four combed ends ultimately being combined into a single sliver and passed to a delivery can. The short fibers, neps and vegetable matter, commonly collectively called noils, remain in the pins of the small circle and are subsequently removed.

In the form shown of the present invention, three inner circles are provided within the outer circle, the inner circles being spaced at substantially equal intervals of about 120°. The three circle construction not only increases machine production by about 50% but also produces 50% more ends to be combined into the single sliver fed to the delivery can, thus averaging out in the combing process itself inequalities of the sliver and reducing the number of subsequent drawing and doubling operations required to produce a finished yarn.

Another feature found in the present inven-

2
tion is that the outer circle is stationary and the sliver feed supply does not revolve around the axis of the large circle as in the conventional Noble comb, the inner circles being rotated on the axis of the outer circle in a planetary motion together with the drawing off rolls and aprons, dabbing motions, star wheels, false twist motions and accessories. This construction permits the feeding of slivers from cans or from larger balls than is feasible in the usual construction in which the slivers being fed to the machine are unreeled from balls rotating with the large circle upon its axis. Consequently, this invention yields a more uniform and homogeneous combed sliver and reduces the number of splicing operations required of the machine operator.

Another feature of the invention is that the drawing off rollers and aprons are automatically vertically reciprocated to equalize wear on the aprons and drawing off rolls from the passage of the slivers. In the conventional Noble comb, only the aprons are reciprocated.

Among the objects of the present invention are to provide a circular comb of greatly increased production capacity; to provide a machine that will produce a more uniform homogeneous sliver; to provide a circular comb in which the sliver supply is not rotated, so as to permit feeding from larger balls or cans; and to provide an improved system of drawing off rolls and aprons.

Another object is to generally improve circular combing machines.

35 Further objects and objects relating to details and economies of construction and use will more definitely appear from the detailed description to follow.

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The form in which I have contemplated applying my invention is illustrated in the accompanying drawings forming part of this specification, in which:

Fig. 1 is a diagrammatic top plan view of a combing machine constructed according to the present invention. Parts of the machine have been omitted or broken away for clarity of illustration.

Fig. 2 is a somewhat diagrammatic perspective view of a portion of the machine of Fig. 1, showing a modified method of feeding the slivers to the machine.

Fig. 3 is a diagrammatic elevation of the drive for the various elements of the machine including the drawing off rolls and aprons, small circles, rotating center element and the false twist motions.

Fig. 4 is a somewhat diagrammatic perspective view of a mechanism for reciprocating the drawing off rolls and aprons.

Referring to Fig. 1, the wool to be combed is in sliver form and, as illustrated, has previously been wound into the balls 10, each ball having four ends that can be pulled off simultaneously. The balls 10 may be supported in racks 11 formed of a pair of rollers. The racks 11, which are arranged about a large outer combing circle 15, are schematically shown in Fig. 1. Functionally, this is the usual method of feeding slivers into a so-called Noble type of combing machine, except that the whole feed supply and mechanism does not revolve around the axis of the large circle.

If desired, the slivers may be supplied from stationary cans as indicated in Fig. 2 so as to eliminate the balling operation or larger than customary balls may be used, this being facilitated by a construction in which the feeding mechanism and the heavy balls of slivers being supplied to the machine are stationary rather than rotated with the large combing circle as in conventional construction.

Each sliver is brought through a feed box 12, the feed boxes extending radially outward from the outer circle 15. Each feed box 12 forms a channel for feeding an uncombed sliver to the outer circle 15, and is pivotally mounted on a horizontal transverse pivot below its outer end. Each feed box has a transversely pivoted cover 14 which may be raised to insert a sliver into the feed box. The cover 14 presses down on the sliver due to its own weight and prevents outward withdrawal of the sliver from the feed box. The feed boxes are successively rocked about their pivots to feed the slivers into the combing machine. The feed box arrangement as described in this paragraph is conventional.

A large horizontal outer circle 15 is provided, this circle being more or less standard and having an inner diameter of about 42½ inches. The circle is provided with several rows of closely spaced pins 16 arranged in rows extending through the top surface of the circle and projecting upward, as is customary. There are many thousands of pins 16 on the circle 15, extending to the inner circumference of the circle. In the preferred form of the invention, the outer circle, the feed boxes and the balls of wool 10 together with the racks 11 are all stationary rather than being rotated as a unit about the axis of the outer circle as in the conventional machine.

A plurality of inner circles 17, preferably three or more in number, are located inside of and tangent to the inner circumference of the outer circle 15. The inner circles 17 are standard and customarily 16 inches in diameter. These circles are each provided with concentric rows of many very closely spaced pins 19, the pins 19 extending upward through the top surface of each circle 17 adjacent to the outside edge of the circles. The circles 17 are rotated on their own axes and are supported on a framework including a round

plate 20 which carries the various parts to be described later.

For proper combing operation of the machine, it is necessary to heat the outer and inner combing circles 15 and 17, as is usual practice. This is accomplished by an arcuate heater 98 (Fig. 3) located below each inner circle 17, and a similarly shaped heater 99 located immediately below the outer circle 15. The heaters 98 and 99 are preferably electric resistance heaters, but conventional steam heaters may be used. A tube 100 for receiving steam may also be located beneath the outer circle 15 for heating it.

In operation of the machine, the inner circles 17 are rotated on their axes in the direction indicated in Fig. 1 and at the same time the framework, including the plate 20, is rotated as indicated about the axis of the outer circle 15, the inner circles 17, in effect, rolling about the inner circumference of the stationary outer circle. Actually, slight clearance is maintained between the inner circles and the outer circle, and the rotative speed of the inner circles is such that there is practically no relative movement at the point of tangency between the inner circles and the outer circle, the inner circles being moved in a planetary motion. The plate 20, with attached mechanism, including the inner circles 17, is rotated as a unit within the outer circle 15 at a normal operating speed of about 4 or more revolutions per minute.

A dabbing brush 21 is located and maintained above the point of tangency of each inner circle 17 with the outer circle 15. The dabbing brushes 21 are reciprocated upwardly and downwardly very rapidly by conventional mechanism, not shown, in order to press the uncombed slivers into the pins of both the outer circle 15 and the inner circles 17 at the points of tangency, which points progress around the inner circumference of the large circle in the direction indicated as the inner circles are rotated about the axis of the outer circle. Preferably, the dabbing brushes 21 are each operated by an electric motor. In order to prevent excessively rapid wear on the dabbing brushes, it is necessary that there be as little movement of the circles as practicable when the bristles of the dabbing brushes 21 are engaged with the pins of the circles at the end of their downward stroke. Accordingly, the dabbing brushes are given a very rapid up and down motion.

In the operation of the machine, the pairs of drawing off rolls are located functionally following the points of tangency of the inner circles 17 and the outer circle 15. A driving drawing off roll 22 is located adjacent the inner circumference of the outer circle 15, as indicated in Fig. 1, following the point of tangency of each inner circle 17. The drawing off rolls 22 are usually fluted, and drive the driven fluted roll 24 by contact through an interposed apron 25. The rolls 24 are pressed towards the rolls 22 by springs in the customary manner.

The apron or belt 25, which is usually formed of leather, extends in a generally triangular path as indicated in Fig. 1, the apron passing between the drawing off rolls 22 and 24. A pair of idler rolls 26, 26 also support the apron 25 and an apron guide 27 holds the apron near the inner circumference of the outer circle 15. Thus, there are three aprons 25, one for each circle 17.

The operation of the machine is such that the inner circles 17 progress in a planetary motion

along the inner circumference of the outer circle 15 in the direction indicated in Fig. 1. Part of the sliver that has been dabbed into the pins 16 and 19 at each point of tangency will be pulled through the pins as the circles diverge, separating the pins, the individual fibers being retained in either one or the other set of pins and forming a combed fringe projecting from both circles. Hence, there will be a fringe of combed fibers projecting inwardly from the inner circumference of the outer circle 15 and outwardly from the outer circumference of the inner circle 17, the remaining portions of the fibers in the fringe remaining in the pins of their respective circles in an uncombed condition.

As each apron 25 moves with its circle 17 in a counterclockwise direction about the axis of the outer circle 15, the apron simultaneously is moving in a clockwise direction about the rolls 24 and 26 at a greater relative linear velocity than that of the rolls 22 and 24 along the inner circumference of circle 15, as indicated in Fig. 1, the apron serving to direct the loose ends of the fibers supported on the large circle 15 towards the nip of the drawing off rolls 22 and 24. As the projecting fringe of combed fibers reaches the drawing off rolls, it is nipped and the remaining uncombed lengths of the fibers are pulled through the pins 16 of circle 15 thus being combed and passed between the rolls along with the aprons 25. Since the operation is continuous, an end of combed sliver is formed which is carried inwardly along the face of the apron.

The fibers carried as a fringe on each inner circle 17 are oriented towards a second pair of drawing off rolls 30 and 31 by a star wheel 29 adjacent each small circle. Each star wheel 29 rotates on a horizontal axis somewhat above the circles and projections extend radially outwardly on the periphery of the star wheel, these projections at the lower portion of the wheel engaging the fibers and pointing them towards the drawing off rolls for each inner circle. Each star wheel 29 may be driven from the motor driving the adjacent dabbing brush. The inner circle and star wheel relationship is conventional and well known in the art.

The drawing off rolls for each inner circle comprise a driving drawing off roll 30 and a driven drawing off roll 31, these rolls being generally similar to the rolls 22 and 24. The driven roll 31 is driven by frictional engagement with a leather apron 32 passed between the rolls. The apron 32 extends beside a portion of the apron 25, as indicated in Fig. 1, both of these aprons aiding in supporting and progressing the end coming off the outer circle. The apron 32 is carried on a pair of idler rollers 34 and directs the ends of the projecting fibers of the inner circle 17 between the drawing off rolls 30 and 31 in the manner of the apron 25 above described. The end from the outer circle 15 and the end from the inner circle 17 are "doubled" at the drawing off rolls 30 and 31 into a common end.

The other two inner circles 17 operate in a like manner in association with the outer circle to produce a composite end combined from the individual ends delivered by each pair of drawing off rolls 30 and 31. The composite or combined ends then pass inwardly to a rapidly rotating funnel or so-called false twist trumpet 35 which is rapidly rotated on the axis of the outer circle 15 with which its axis coincides. The trumpet 35 combines the composite ends from each pair of drawing off rolls 30 and 31 into a single sliver

formed of six individual ends and puts a false twist into the sliver. The combined sliver is conducted upwardly a sufficient distance to clear the rotating portions of the machine and into a second false twist trumpet 32 which may be revolved usually in the opposite direction as illustrated in Fig. 3, the false twist only serving to give strength to the sliver to take it from the machine. The sliver is then passed through a third revolving false twist trumpet where the false twist is removed thence into a can, preferably by a conventional can coiler (not shown) or wound into a ball on a conventional balling head (not shown).

The noil (short fibers, neps and vegetable matter) is retained within the pins 19 of each inner circle 17 since these fibers do not project sufficiently from the inner circles to be caught and drawn by the nip (point of contact of the drawing off rolls 30 and 31). The noil is carried in the pins 19 to the noil brush 36 which is a circular brush free to revolve on a substantially horizontal axis and having its bristles engaged against the pins 19 to revolve the brush. The noil brush 36 serves to raise the noil to the top of the pins 19, and curved stationary noil knives (not shown) located between the rows of pins direct the noil into a noil chute or duct 37 leading to a noil receptacle. The noil brushes and noil knives are conventional.

The feed mechanism for the uncombed slivers will now be described in greater detail. The uncombed slivers are fed inwardly over the outer circle 15 by increments in an amount about equal to the width of the rows of pins of each inner circle 17, and this feed must take place between the drawing off rolls 22 and 24 associated with one inner circle 17 and the point of tangency of the following inner circle 17. This feed is produced by rocking each feed box on its pivot so as to raise the inner end of the feed box, the ends of the slivers being held in the pins 16 of the outer circle by the adjustable feed knives 42 as shown in Fig. 2, the ball 10 being rotated slightly to give the necessary slack in the sliver.

The ball 10 may be rotated by a ratchet feed arrangement, well known in the art, for intermittently rotating the rolls forming the rack 11. The ratchet feed may be actuated by cams (not shown) revolved with the plate 20, one cam being provided for each inner circle 17.

The feed boxes are successively raised by the feed box cams 39 (one for each inner circle) carried on the feed box cam ring 40 extending under the feed boxes and rotating with the plate 20 to rock the feed boxes on their pivots. This moves the inner end of the feed box together with the sliver (which is located somewhat above the pivot) upwardly. Simultaneously, concentric curved feed knives 42 (Fig. 2), the outer one of which is located adjacent the outer row of pins of the outer circle 15, hold the uncombed sliver in the pins 16 of the outer circle. The feed knives 42 (see Fig. 2) are adjustable vertically to vary the length of the feed and are mounted on the plate 20 and rotated in a circle about the axis of the outer circle 15. Holding the sliver end in the pins of the circle 15 while raising the inner end of the feed box 14 advances the uncombed sliver through the feed box. Following this, lifting knives (not shown) placed between each row of pins of circle 15 and revolving with plate 20 lift the sliver out of the pins 16. After the sliver has been freed from the pins of circle 15, the feed box cam 39 terminates so as to permit the feed box 12 to drop to its normal position. This allows

the ends of the slivers to move inwardly where they are held above the pins 16 by a plate (not shown) until the dabbing point (point of tangency) is reached. The sliver is then in position to be dabbed into the pins 16 and 19 of the outer and inner circles by the dabbing brush 21. This feed is functionally the same as in conventional combs.

The above-described feed occurs successively along the line of feed boxes as the inner circles 17 rotate in their orbit about the axis of the outer circle 15. The feed takes place simultaneously at three equally spaced points about the outer circle.

The feed of the machine may be rendered more uniform by feeding each sliver independently from a separate can 101, as indicated in Fig. 2. In such an arrangement, each sliver may be fed at a speed regulated by the feed cams 39 and feed knives 42 and not affected by the other slivers of the ball (as in the conventional machine) or the then diameter of the ball. This feed arrangement gives a more uniform sliver with less adjustment of the feed knives.

Maintenance and replacement of the aprons of conventional circular combing machines represent a very substantial portion of the operating expense. In the form shown of the present invention, in order to equalize wear on the aprons 25 and 32, the aprons together with the drawing off rolls 22, 24, 30 and 31 and the idler rolls 26 and 34 are slowly reciprocated over a vertical interval of about $2\frac{1}{4}$ inches to prevent the slivers coming off the circles from running on the same portion of the aprons at all times. This is accomplished by carrying the drawing off rolls and idler rolls on a horizontal plate 44 (Fig. 4) which is slowly reciprocated in a vertical direction, the plate including stiffening members mounted on the underside thereof.

Referring to Fig. 4, the mechanism for reciprocating the plate 44 comprises an electric motor 45 which is supported by the plate 20 of the combing machine and drives an internally threaded sleeve 46 through a speed-reducing gear train 47 and a universal joint 49. A rod 50 is threadedly engaged with the sleeve 46, the rod being pivotally connected to a lever 51 fixed to a cross shaft 52 journaled in bearings 54 fixed to the revolving plate 20 of the machine. Two levers 55, 55 fixed to the shaft 52 are pivotally connected with the plate 44 by links 56, 56.

The opposite side of the plate 44 is supported and simultaneously reciprocated by a mechanism including an arm 57 fixed to the shaft 52 and in the plane of the arm 51. A link 59 connects the arm 57 with a similar arm 60 fixed to a shaft 61 parallel to the shaft 52 and supported in a bearing 62 supported on the revolving plate 20 of the machine. A lever 64, similar to the levers 55, 55, is connected with the plate 44 by a link 65. Oscillation of the shaft 52 serves to alternately raise and lower (reciprocate vertically) the plate 44 in suitable guides (not shown).

The motor 45 is periodically reversed by an electric switch 66 which is operated by a projecting finger 67 carried by the shaft 50. The sleeve 46 is periodically reversely rotated as the finger 67 moves back and forth with the rod 50, reciprocating the rod and oscillating the shaft 52 to vertically reciprocate the plate 44 upon which the drawing off rolls and idler rolls are carried.

The foregoing mechanism slowly vertically reciprocates the drawing off rolls, idler rolls and aprons through a distance of about $2\frac{1}{4}$ inches so

as to spread the wear on the aprons and the drawing off rolls.

The driving mechanism for the combing machine is shown diagrammatically in Fig. 3. The machine is driven by an electric motor (not shown) which is located near the base of the machine to minimize vibration and which drives a shaft 69 connected with a gear box 70. A shaft 71 leads from the gear box and, turning at reduced speed, drives a pinion 72 meshing with a large gear 74. The gear 74 is stationary and fixed to the stationary frame of the combing machine, the motor and the gear box 70 being carried on a frame, not shown, of which the plate 20 is a part and which is mounted for rotation about the axis of the outer circle 15. The pinion 72 rotates this frame at a speed of 4 or more revolutions per minute.

Each inner circle 17, which rotates about the axis of the outer circle on the rotating frame plate 20, is supported on a small circle plate 18 and driven from the gear 74 by a shaft 75 having pinions 76, 76 at either end, the upper pinion 76 meshing with an inner circle driving gear 77 located immediately below the small circle plate 18. Although the drive for only one inner circle 17 has been shown, the other two circles are driven in a similar manner.

The drawing off rolls 22 and 24 are driven from the gear box 70 through universal joints 79 and gear train 80 driving a shaft 81 which in turn drives a crown gear 82 journaled on the axis of the outer combing circle 15. The gear 82 in turn drives a shaft 84 which drives the drawing off roll shaft 85. The other two pairs of drawing off rolls 22 and 24 are similarly driven from the gear 82.

For driving the drawing off rolls 30 and 31, a second crown gear 86 is driven from the gear train 80 by means of a shaft 87, this crown gear driving a large spur gear 89 located on the axis of the outer combing circle 15 and driving the drawing off roll shaft 90 of the drawing off roll 30. The other two pairs of drawing off rolls 30 and 31 are similarly driven from the gear 89.

The gear train 80 together with the gears 82, 86 and 89 and the drawing off rolls and their drive shafts are vertically reciprocated with the plate 44, the universal joints 79 allowing for this vertical movement. In addition, all these parts together with the motor and the gear box 70, plate 20, and associated parts are rotated about the axis of the outer circle 15.

A shaft 91, driven from the shaft 69, serves to drive the trumpet 35 and a second trumpet 92, the first trumpet putting a false twist into the combed sliver coming from the pairs of inner drawing off rollers 30 and 31 and the second reversing the false twist. These trumpets may be driven by belts from the shaft 91, the trumpets turning in opposite direction. As above noted, the trumpet 35 is preferably rotated on the axis of the outer circle 15. The trumpet 92 may also be rotated on this axis, the sliver being taken off laterally from above this trumpet.

A can coiler, not shown, of conventional construction may be driven from the hub of the gear 82 by a shaft 94 located on the axis of the outer circle 15. The shaft 94 is not reciprocated with the gear 82, a slip joint 95 being provided at its upper end. A laterally extending shaft 96 driven from the shaft 94 is connected with the can coiler. If desired, the machine may be driven through the shaft 96 of the can coiler drive, rather than

driven by a motor rotated with the inner circles and associated mechanism.

The mechanism for operating each dabbing brush 21 may be carried from shaft or column 97 (Fig. 3). The column 97 is not rotated on its own axis nor reciprocated vertically, but is rotated about the axis of the outer circle 15 with the plate 20.

I claim:

1. In a circular combing machine for textile fibers, a large outer combing circle and a plurality of inner combing circles tangent to the outer circle, means fixedly mounting the outer circle with reference to a support, means for rotating the inner circles in a planetary motion along the inner circumference of the outer circle, and guide means located on the axis of the outer circle for receiving the combed sliver and conducting it axially from the machine.

2. In a circular combing machine for textile fibers, a large outer combing circle and a plurality of inner combing circles tangent to the outer circle, means fixedly mounting the outer circle with reference to a support, means for rotating the inner circles in a planetary motion along the inner circumference of the outer circle, and a rotating trumpet having its axis of rotation substantially coincident with the axis of the outer circle for receiving the combed sliver and conducting it axially from the machine.

3. In a circular combing machine for textile fibers, a large outer combing circle and a plurality of inner combing circles tangent to the outer circle, means fixedly mounting the outer circle, means for rotating the inner circles in a planetary motion along the inner circumference of the outer circle, and a pair of oppositely rotating trumpets having their axes substantially coincident with the axis of the outer circle for receiving the combed sliver and conducting it axially from the machine.

4. In a circular combing machine for textile fibers, the machine having a large outer combing circle, a plurality of inner combing circles tangent to the outer circle, and pairs of drawing-off rolls positioned adjacent the outer and inner circles for drawing the combed fibers therefrom, the improvement which comprises: means fixedly mounting the outer circle, means supporting the inner circles and drawing-off rolls for rotation about their own axes, and means for rotating said inner circles and drawing-off rolls about their own axes and for rotating said supporting means about the axis of the outer circle.

5. In a circular combing machine for textile fibers, the machine having a large outer combing circle, a plurality of inner combing circles tangent to the outer circle, and pairs of drawing-off rolls positioned adjacent the outer and inner circles for drawing the combed fibers therefrom, the improvement which comprises: means fixedly mounting the outer circle, a single support mounting the inner circles, and drawing-off rolls for rotation about their own axes, means for rotating said support about the axis of the outer circle, and means for rotating the inner circles on their axes, including a gear concentric with the outer circle.

6. In a circular combing machine for textile fibers, the machine having a large outer combing circle and a plurality of inner combing circles tangent to the outer circle, the improvement which comprises: means fixedly mounting the outer circle and means for rotating the inner

circles in a planetary motion along the inner circumference of the outer circle.

7. In a circular combing machine for textile fibers, the machine having a large outer combing circle and an inner combing circle tangent to the outer circle, the improvement which comprises: means fixedly mounting the outer circle and means for rotating the inner circle in a planetary motion along the inner circumference of the outer circle.

8. In a circular combing machine for textile fibers, the machine having a large outer combing circle, a plurality of inner combing circles tangent to the outer circle, and pairs of drawing-off rolls operating adjacent the outer circle for drawing the combed fibers from the outer circle and the inner circles, the improvement which comprises: means fixedly mounting the outer circle, means for rotating the inner circles and the drawing-off rolls in unison about the axis of the outer circle, and means for rotating the inner circles and drawing-off rolls on their own axes.

9. In a circular combing machine for textile fibers, a large outer combing circle and a plurality of inner combing circles tangent to the outer circle and spaced along the outer circle at substantially equal intervals not in excess of 120°, means fixedly mounting the outer circle with reference to a support, and means for rotating inner circles on their own axes and also about the axis of the outer circle to produce a rolling motion of the inner circles about the inner circumference of the outer circle.

10. In a circular combing machine for textile fibers, a large outer combing circle and a plurality of inner combing circles tangent to the outer circle and spaced along the outer circle at substantially equal intervals of approximately 120°, means fixedly mounting the outer circle with reference to a support, and means for rotating inner circles on their own axes and also about the axis of the outer circle to produce a rolling motion of the inner circles about the inner circumference of the outer circle.

11. In a circular combing machine for textile fibers, a large outer combing circle and a plurality of inner combing circles tangent to the outer circle, means fixedly mounting the outer circle with reference to a support, means for rotating the inner circles in a planetary motion along the inner circumference of the outer circle, dabbing brush mechanism located above the circles and rotated with the inner circles for applying uncombed slivers to the circles at the points of tangency, and means for taking the combed sliver from the machine above the level of the dabbing brush mechanism.

12. In a circular combing machine for textile fibers, a large outer combing circle and a plurality of inner combing circles tangent to the outer circle, means fixedly mounting the outer circle with reference to a support, means for rotating the inner circles in a planetary motion along the inner circumference of the outer circle, mechanism for successively feeding individual uncombed slivers to the machine at the point of tangency of the circles, and means for supplying each individual uncombed sliver to the feed mechanism independently of the supply of the adjacent slivers.

13. In a circular combing machine for textile fibers, a large outer combing circle, a plurality of inner combing circles tangent to the inner combing circle, and drawing-off rolls and aprons adjacent the outer and inner circles for taking

11

the fibers from the circles and feeding ends towards the center of the machine, means supporting the drawing-off rolls and aprons, said supporting means being mounted for vertical reciprocation and means, including a reversible electric motor and means causing reversal of said motor at each end of the vertical travel of said drawing-off roll and apron-supporting means for vertically reciprocating the drawing-off rolls and aprons slowly past the circles.

14. The method of combing fibers of wool and the like, comprising maintaining an outer combing circle stationary, rotating an inner combing circle along the inner circumference of the outer combing circle in a planetary movement, and 15 combing the fibers between the outer combing circle and the inner combing circle as a result of the divergent paths of the circles.

15. The method of combing fibers of wool and the like, comprising maintaining an outer comb- 20 ing circle stationary, rotating a plurality of inner

5

combing circles along the inner circumference of the outer combing circle in a planetary movement, and combing the fibers between the outer combing circle and the inner combing circles as a result of the divergent paths of the inner and outer combing circles.
